GREENHOUSE CONSTRUCTION

James B. Foley, River Forest, Ill., assignor to The
Foley Greenhouse Manufacturing Company, a
corporation of Illinois

Application May 20, 1932, Serial No. 612,569

6 Claims. (Cl. 108—25)

The invention relates to greenhouse construction and has for its primary object the provision of improved construction of the kind described which is durable and may be erected with a minimum of labor.

Another object of the invention is to provide improved construction of the kind described which will permit wooden members thereof to be protected thoroughly against the deteriorating effects of moisture.

Another particular object of the invention is to provide an improved roof bar bracket for securing the wooden roof bars or rafters to the gutter channels, or the equivalent, at the eaves of the buildings.

Still another object of the invention is to provide construction of the kind described having improved means for holding the glass of the roof.

20 Other objects and advantages will become apparent as the following detailed description progresses, reference being had to the accompanying drawings, wherein

Figure 1 is a section taken transversely through the eaves of a greenhouse which embodies the invention, the section being taken on line 1—1 of Fig. 4.

Fig. 2 is a section taken on the same line as Fig. 1, but the glass of the roof and a glazing strip for holding it are omitted.

Fig. 3 is a section taken on line 3—3 of Fig. 2.

Fig. 4 is a plan view of the apparatus shown in Figs. 1 and 2.

Fig. 5 is a side elevation of an improved roof bar bracket for securing the roof bars or rafters to a channel which forms a gutter between adjacent units of a greenhouse.

Fig. 6 is a plan view of the improved roof bar bracket.

Fig. 7 is an end elevation of the improved roof bar bracket, and

Fig. 8 is a perspective view of one of a plurality of glazing strips which co-operate with the gutter channel and the roof bar brackets to hold the lowermost glass on the roof of the improved structure.

Referring to the drawings, the reference character 10 designates a metal channel which forms a gutter in the valley between adjacent units of a greenhouse. It will be noted that the web 11 of the channel 10 is disposed substantially horizontal and that it is crowned slightly as at 12 so that its bottom surface is slightly concave. This construction insures that any water which collects or condenses upon the bottom surface of the chan-

nel or drips from the outer vertical surfaces of the legs thereof, will flow to or will collect along the longitudinally extending edges of the bottom surface of the channel and fall into gutters hereinafter described.

The channel 10 is secured by bolts 15 to post brackets, one of which is shown at 16. The brackets 16 are provided with sockets 17 which communicate the upper ends of posts or columns 18. The lower ends of the posts 18 are preferably embedded in concrete foundation blocks (not shown), or the equivalent.

As best shown in Fig. 2, the bracket 16 is provided preferably with integral laterally extending V-shaped arms 19 which carry gutters 20, or the equivalent.

A fragmentary portion of an improved greenhouse roof is illustrated in connection with the channel 10, the greenhouse roof being designated generally by the reference character 22. The roof 22 comprises a plurality of wooden roof bars or rafters, one of which is shown at 23. The roof bar 23 is shown in cross section in Fig. 3. Its upper portion is reduced in width to provide shoulders 24 for supporting the glass 25 of the roof. It will be noted that the edges of the glass 25 rest upon putty 26, or the equivalent, and that brads 27, or the equivalent, hold the glass rigidly in place upon the roof bars. The roof bar 23 is also provided with grooves or channels 28 in its side surfaces, which channels 28 collect condensation from the roof bar and discharge it at the lower end thereof, the lower end of the roof bar being adjacent the channel 10.

The roof bar 23 is secured to the channel 10 by means comprising an improved roof bar bracket 30. The roof bar bracket 30 is preferably cast from metal and comprises a relatively thin, vertically extending web portion 31. Formed integral with the web portion 31 at the upper end thereof is a head portion 32 and formed integral with the lower end of the web portion 31 is a foot portion 33. The foot portion 33 is provided with a notch 34 having surfaces adapted to abut against a side surface and the bottom surface of the channel 10. (See Figs. 1 and 2.) The foot portion 33 is also provided with a lug 34a against which one may hammer or pound to assemble the bracket 30 with the channel 10.

The head portion 32 is formed with a notch 36 which is engageable with the free edge of one of the flanges of the channel 10. When the bracket 30 is to be assembled with the channel 10, the notch 36 of the bracket 30 is first engaged with the channel 10 in the manner illustrated in

60

65

70

75

80

85

90

95

100

105

110

Figs. 1 and 2. The foot portion 33 is then driven into the position wherein it is shown in the same figures. The bracket 30 is designed to fit snugly on the channel 10 and therefore it is necessary 5 to hammer or pound upon the lug 34a to drive the foot portion 33 into the position wherein the surfaces of the notch 34 engage the channel 10 in the manner illustrated in Figs. 1 and 2.

The head portion 32 is provided with a pair of 10 integral laterally extending lugs 37 and a pair of integrally extending lugs 38. The lugs 37 hook over the free edge of the channel flange to which the bracket 30 is secured. (See Figs. 1 and 2.) The lugs 37 also form stops for the ends of the 15 sheet metal glazing strips 40. The glazing strips 40 are preferably formed from zinc.

The lugs 38 form continuations of the shoulders 24 provided upon the roof bar 23 and therefore support the glass 25. It will be noted that the 20 ends of the glazing strips 40 abut against the side surfaces of the head portion 32 and are disposed between the lugs 37 and 38. This construction insures that the glazing strips 40 will remain in place upon the upper edge of the channel leg to 25 which the bracket 30 is secured.

Formed integral with the web 31 and extending laterally therefrom are a pair of ribs 42 and a pair of ribs 43, which ribs 42 and 43 extend from the head portion 32 and the foot portion 33, 30 respectively. The ribs 42 and 43 converge into an integral arm 45 to which the lower end of the roof bar 23 is secured by a screw 46, or the equivalent. It will be noted that the arm 45 supports the lower end of the roof bar. The ribs 42 and a 35 portion of the arm 45 are curved to provide an arcuate surface 47 spaced from the lower end of the roof bar. As indicated at 50 in Figs. 1 and 2, sufficient space is left between the surface 47 and the lower end of the roof bar so that the major 40 portion of the lower end of the roof bar may be painted to protect it against the deteriorating effect of moisture.

The head 32 of the bracket 30 is secured to the lower end of the roof bar 23 by a wood screw 52, or the equivalent, which extends diagonally 45 into the roof bar. It will be noted that the head of the screw 52 is counter-sunk in the head 32 of the bracket 30.

Each glazing strip 40 is bent to provide a flange 50 55 which engages the lower edges of the glass 25. An intermediate portion 56 of the glazing strip 40 extends at right angles to the flange 55 and supports the lower marginal portion of the bottom surfaces of the glass 25. The glazing strip 40 also comprises a substantially vertically disposed flange 57 which abuts against the outer 55 surface of the channel flange to which the bracket 30 is attached.

The notch 34 forms an angular seat and is 60 disposed opposite to the notch 36. The notch 36 forms a hook in the head 32. This hook and the notch 34 co-operate to secure the bracket 30 rigidly to the channel 10, the bracket being locked to the channel by a wedge-like action.

It will be noted that the moisture collected by 65 the channels 28 in the bar 23 will be discharged or drip into the gutter 20 disposed beneath the bracket 30. It will also be noted that all moisture which condenses upon the under side of the glass 25 or on the bracket 30 will drop into this gutter 20. The gutter 20 will also receive the moisture which drips from the lower edge of the outer surface of the channel flange to which the bracket 30 is secured.

70 While I have shown and described certain em-

bodiments of my invention, it is to be understood that it is capable of many modifications. Changes, therefore in the construction and arrangement may be made without departing from the spirit and scope of the invention as disclosed in the appended claims, in which it is my intention to claim all novelty inherent in my invention as broadly as possible, in view of the prior art.

80

I claim:

85

1. In a building, a member extending along the eaves thereof, a rafter extending at right angles to said member, a bracket secured to one end of said rafter and to said member, said bracket being provided with laterally extending lugs, a glazing strip mounted on said member and having one of its ends disposed between said lugs to prevent displacement of said strip laterally of said member, and a glass pane abutting said strip.

90

2. In a building, a member extending along the eaves thereof, a rafter extending at right angles to said member, a bracket secured to one end of said rafter and to said member, said bracket being provided with laterally extending lugs, a glazing strip mounted on said member and having one of its ends disposed between said lugs to prevent displacement of said strip laterally of said member, and a glass pane abutting said strip.

95

3. In a building, a member extending along the eaves thereof, a rafter extending at right angles to said member and provided with a longitudinally extending shoulder, a bracket secured to one end of said rafter and to said member, said bracket being provided with laterally extending lugs, a glazing strip mounted on said member and having one of its ends disposed between said lugs to prevent displacement of said strip laterally of said member, and a glass pane abutting said strip, said glass pane being supported by said strip and having its bottom surface resting on one of said lugs.

100

3. In a building, a member extending along the eaves thereof, a rafter extending at right angles to said member and provided with a longitudinally extending shoulder, a bracket secured to one end of said rafter and to said member, said bracket being provided with laterally extending lugs, a glazing strip mounted on said member and having one of its ends disposed between said lugs to prevent displacement of said strip laterally of said member, and a glass pane abutting said strip, said glass pane being supported by said strip and having its bottom surface resting on one of said lugs.

110

4. In a building, a channel providing a gutter between two building units having wooden rafters, said channel having its flanges substantially vertically disposed, a bracket secured to the outer end of one of said rafters and to one of the flanges 125 of said channel, said bracket being provided with laterally extending lugs, a glazing strip positioned on the upper edge of the last-mentioned flange of said channel, one end of said glazing strip being disposed between said lugs to prevent displacement thereof laterally of said channel, and a glass pane having one of its edges abutting said glazing strip.

120

5. In a building, a channel providing a gutter between two building units having wooden rafters, said channel having its flanges substantially vertically disposed, a bracket connecting a rafter with said channel, said bracket comprising a head portion having a hook engaging a flange of said channel, a foot portion having an angular seat adapted to engage two surfaces of said channel, a web portion connecting said head portion and said foot portion, said web being spaced from the end of said rafter so that said end is readily accessible, a pair of lugs projecting laterally from said head, a glazing strip positioned on the upper edge of the flange of said channel, one end of said glazing strip being disposed in said lugs to prevent displacement thereof laterally of said

135

5. In a building, a channel providing a gutter between two building units having wooden rafters, said channel having its flanges substantially vertically disposed, a bracket connecting a rafter with said channel, said bracket comprising a head portion having a hook engaging a flange of said channel, a foot portion having an angular seat adapted to engage two surfaces of said channel, a web portion connecting said head portion and said foot portion, said web being spaced from the end of said rafter so that said end is readily accessible, a pair of lugs projecting laterally from said head, a glazing strip positioned on the upper edge of the flange of said channel, one end of said glazing strip being disposed in said lugs to prevent displacement thereof laterally of said

140

145

150

channel, and a glass pane having one of its edges abutting said glazing strip.

6. In a building, a bracket for connecting a rafter with a member extending longitudinally of the building, said bracket being provided with an angular seat adapted to engage two sides of said member, and an opposing hook for engaging an edge of said member, said bracket comprising a

head portion secured to said rafter, and an integral arm secured to the bottom surface of said rafter, said bracket being spaced from said rafter intermediate said head portion and said integral arm whereby said end surface of said rafter is readily accessible. 80
